UNITED STATES PATENT OFFICE.

FRANK FREDERICK WEDEKIND, OF SAN FRANCISCO, CALIFORNIA.

FOOT-SUPPORTER.

No. 865,836.

Specification of Letters Patent.

Patented Sept. 10, 1907.

Application filed December 20, 1906. Serial No. 348,680.

To all whom it may concern:

Be it known that I, FRANK FREDERICK WEDEKIND, a citizen of the United States, and a resident of San Francisco, in the county of San Francisco and State of California, have invented a new and Improved Foot-Supporter, of which the following is a full, clear, and exact description.

The purpose of the invention is to provide a form or shape for what is known as flat feet, which will be simple durable light and perfectly shaped to the foot, being adapted to be worn in the shoe; and a further purpose of the invention is to provide a form or support of the character described that will maintain its shape and which will fit up well around the heel and sides of the foot, extending to the ball thereof, the device extending higher up at the inner instep section than at any other point so as to provide the most support thereat.

Another purpose of the invention is to provide the support or form with means whereby to prevent its rocking, and tending to always hold the device in required position.

The invention consists in the novel construction and combination of the several parts, as will be hereinafter fully set forth and pointed out in the claims.

Reference is to be had to the accompanying drawings forming a part of this specification, in which similar characters of reference indicate corresponding parts in all the figures.

30 Figure 1 is a perspective view of the improved device; Fig. 2 is a longitudinal vertical section through the same; Fig. 3 is a bottom plan view of the device; Fig. 4 is a transverse section through the same; and Fig. 5 is an enlarged detail sectional view of a portion 35 of the device, illustrating the manner in which it is constructed.

As stated, the device is particularly adapted to hold up the arch or instep of the foot wherein the arch is broken down or defective, and said device is made up 40 of one or more layers 10 of cotton stockinette, usually two layers that are drawn over a cast of the foot; and said layers of stockinette are provided with a sufficient number of layers 11 of dissolved celluloid to penetrate the stockinette and effectively fill up all the interstices 45 therein. A thickness of material of about one-eighth to five-thirtysixths of an inch have been found effective; but I do not confine myself to any specific amount of material or thickness of the form or support.

50 Before the form or supporter A is completed, steel strips, usually two in number and designated as 12 and 13, are introduced longitudinally between the layers

of stockinette, as is best shown in Figs. 2 and 4. The form or supporter A thus constructed and shaped comprises a heel section 14, an instep section 15 and a ball 55 section 16, together with a marginal flange 17 that extends continuously along all of the sections with the exception of the forward end of the ball section 16; and the flange 17 at the inner side of the instep section 15 of the form or supporter is carried much higher up 60 than the remaining portion of the flange as is shown at 18 in Figs. 1 and 4, so as to give a maximum of support to the small bones of the instep.

The spring strips 12 and 13 serve to maintain the shape of the supporter at its instep portion, and to hold 65 up the defective portion of the foot. In placing the spring strips, the strip 12 extends longitudinally at or about the lower central portion of the supporter, while the strip 13 extends longitudinally along that portion of the supporter where the inner flange connects with 70 the instep portion of the body or bottom part of the supporter as is shown in Figs. 3 and 4. Preferably the strip 13 is made to diverge more or less at its forward end from the central strip 12. It will be observed that the strips 12 and 13 are securely held in pockets formed 75 by the layers of the stockinette material.

Feet 19, preferably two in number, are employed in connection with the bottom portion of the supporter, one foot being located at the heel section preferably between the rear face of the strips 12 and 13, while 80 the other foot is located at the ball section between the forward ends of said strips 12 and 13. The bottom faces of the feet are flat, and the object of these feet is to prevent the supporter from rocking while in use, serving thus to hold it in steady position, and preventing 85 any particular parts from chafing the feet. Supporters of this type quickly become foul, and none of those of which I have knowledge can be cleanly washed. My improvement renders these devices perfectly sanitary, since they can be quickly washed and rendered 90 absolutely clean.

Having thus described my invention, I claim as new, and desire to secure by Letters Patent,—

1. A foot supporter, comprising a flanged body formed of stockinet and celluloid and shaped to the heel, instep and ball of the foot, the flange extending from the forward end of the ball portion around the heel portion.

2. A foot supporter, comprising a flanged body formed of layers of stockinet and celluloid between the layers and on the outer faces thereof, the body being shaped to the heel, instep and ball of the foot and the flange extending from the forward end of the ball portion around the heel.

3. As an improved article of manufacture, a foot supporter consisting of stockinet saturated with dissolved celluloid and shaped to the bottom and side portions of

the heel, instep and bottom of the foot, and strips extending longitudinally of the said supporter at its instep portion, which strips are incorporated in the said structure.

4. As an improved article of manufacture, a foot supporter constructed of layers of stockinet saturated with dissolved celluloid and shaped to the heel, the instep and ball sections of the foot and to the sides of said sections, strips longitudinally located at the instep portion of the structure, being held between the layers constitut-

ing the same, and means at the bottom portion of the 10
supporter to prevent said supporter from rocking.

In testimony whereof I have signed my name to this
specification in the presence of two subscribing witnesses.

FRANK FREDERICK WEDEKIND.
